UNITED STATES PATENT OFFICE.

LOUIS HILL, OF AKRON, OHIO.

AUTOMATIC GAS-SHUT-OFF MECHANISM.

Application filed January 16, 1924. Serial No. 686,476.

To all whom it may concern:

Be it known that I, LOUIS HILL, a citizen of the United States, and resident of Akron, in the county of Summit and State of Ohio,

have invented certain new and useful Improvements in Automatic Gas-Shut-Off Mechanisms, of which the following is a full, clear, and concise description.

My invention relates to automatic gas shutoff mechanisms, my more particular purpose being to produce a device of this character suitable for use upon small gas burners, the arrangement of the parts being such that after the gas has been turned on by hand and lighted, if, through any ordinary accidental cause the gas flame is extinguished, as for instance by a sudden gust of wind, the flow of gas is immediately cut off by automatic action of parts connected with the burner.

More particularly stated, my invention seeks to improve the efficiency of mechanism of the general type here contemplated, by incorporating therein a toothed wheel of improved form, and various movable parts co-acting with said toothed wheel, looking toward refinement in controlling the movements of the valve used for automatically cutting off the flow of gas.

Reference is made to the accompanying drawing forming a part of this specification, and in which like reference characters indicate like parts throughout the several figures.

Figure 1 is a perspective view showing one form of my device as applied to an ordinary gas burner, certain parts being broken away, the relative positions of various movable parts being such that the flow of gas is shut off and the burner is cold.

Figure 2 is a fragmentary perspective view of the mechanism appearing in Figure 1 and with parts broken away, the movable parts occupying such positions as they should with the gas flowing and the burner hot.

Figure 3 is a detail of the mechanism appearing in Figures 1 and 2, and shows in vertical section the toothed wheel forming an important part of my device.

Figure 4 is a perspective view of another form of my device, parts being broken away, the mechanism being in such condition that the gas is shut off and the burner cold.

Figure 5 is a fragmentary perspective view of the mechanism shown in Figure 4,

certain parts being broken away, the movable parts of the device being in such condition that the gas is flowing and the burner is hot.

Figure 6 is a plan view of a toothed wheel appearing in the form of my device shown in Figures 4 and 5.

A gas pipe 6 is provided with a hand valve 7 and with a burner 8. Enclosing this burner is a globe 9, of the usual or any desired construction.

Located within the globe and secured thereto are a pair of thermostatic bars 10, conveniently designated together as a thermostatic element. This thermostatic element is in close proximity to the burner 8, so as to be readily heated thereby when the burner is in action.

The thermostatic element is so constructed and arranged that when cold it extends slightly upward, as indicated in Figure 1, but when heated by the burner it bends slightly downward, as indicated in Figure 2.

The gas pipe 6 is provided with another valve 11, and connected with this valve is a chain arm 12, to which is connected a pendant chain 13. Integral with the chain arm 12 is an actuating arm 14. This actuating arm and the chain arm together constitute a bell crank lever.

A tensile spring 15 is connected with the actuating arm 14, and with a collar 16. This spring is always under tension and consequently is always pulling upon the actuating arm 14, so that this arm and the various parts immediately associated therewith occupy the respective positions indicated for them in Figure 1 whenever the burner is cold, or in other words whenever it is not actively in use.

Mounted upon the gas pipe 6, at a point just above the valve 11, is a collar 17 fixed in position. Above this collar is a supporting disk 18, provided with a collar portion 19 encircling the gas pipe. Located above the supporting disk and resting loosely upon the same is a toothed wheel 20. The teeth of this wheel each have an edge 20^a, extending radially outward from the axial center of the wheel, and an edge 20^b which is also straight but a little longer than the edge 20^a and is oblique relatively to the axial center of the wheel. For convenience I designate the edge 20^a as radial, and the edge 20^b as slanting.

The teeth of the wheel 20 are so propor-

tioned and so spaced apart at their outer ends that the actuating arm 14 can readily find its way in between them.

An interference arm 22, having in this instance substantially an inverted U-form, is provided adjacent one of its ends with a hole 23, and extending through this hole is a portion 24 of each of the thermostatic bars 10, as indicated more particularly in Figure 2. The interference arm 22 is journaled upon a collar 25, the latter being mounted upon the gas pipe 6, and thus held firmly in position.

A spring 26 is connected with the interference arm 22 and with the collar 25. The purpose of this spring is to take up any lost motion which might otherwise develop between the thermostatic bar 10 and the interference arm, and also to hold the interference arm steady and to add to its precision of movement in engaging and disengaging the teeth of the wheel 20.

The operation of the form of my device appearing in Figures 1 to 3 inclusive may be readily understood from the foregoing description.

In order to light the gas, the operator first actuates the hand valve 7 as is customary with any hand valve used for turning on gas. This done, the operator pulls the chain 13 downwardly, thus rocking the chain arm 12 and the actuating arm 14 slightly in a counter-clockwise direction according to Figure 1, and then lights the gas by hand. The chain is held down by hand for a few moments after the gas is lighted, and is then released.

The burning gas now heats the thermostatic element and causes it to move from the position indicated for it in Figure 1 to that indicated for it in Figure 2, so that the interference arm 22 is rocked slightly in a counter-clockwise direction, and brought into engagement with the teeth of the wheel 20, as indicated in Figure 2. This prevents the wheel 20 from turning, so that when the chain 13 is released the actuating arm 14, now controlled solely by the tension of spring 15, rests against the slanting edge 20^b of some one tooth of the wheel 20.

The apparatus remains in this condition so long as the gas continues to burn, or in other words so long as the burner remains actively in use.

Suppose, now, that through some accidental cause the burner flame is extinguished, as for instance blown out by a sudden gust of wind. The thermostatic element cools off, and in so doing moves from the position indicated for it in Figure 2 to the one indicated for it in Figure 3, and rocking the interference arm 22 back into the position indicated for it in Figure 1. This releases the toothed wheel 20, so that this wheel no longer holds the actuating arm 14. The re-

sult is that the spring 15 rocks the actuating arm 14 and the chain arm 13 back into the positions indicated for them in Figure 1, so that the valve 11 is actuated and cuts off the flow of gas.

Thus although the burner is by hand placed in condition to be lighted, and is also lighted by hand, the closure of one gas valve is always entirely automatic.

When the operator is through using the burner and wishes to turn off the gas, the hand valve 7 is actuated for this purpose; but this is followed as above described by the automatic closure of the valve 11, under control of the thermostatic bar and various parts immediately associated therewith.

In the form of my device appearing in Figures 4 and 5 I use a pair of thermostatic bars 27, supported by the globe 9, these bars when cold appearing as shown in Figure 4, and when heated assuming the form indicated in Figure 5. I designate the pair of thermostatic bars as a thermostatic element.

An interference arm 28 is journaled upon a collar 29, and is provided with a hole 30, through which extends a reduced portion 31 of each of the thermostatic bars.

When the thermostatic element is heated, the interference arm 28 turns in a clockwise direction according to Figure 4, so as to assume the position indicated for it in Figure 5, and when the thermostatic element is cooled, the interference arm rocks in a counter-clockwise direction according to these figures, and assumes the position indicated for it in Figure 4.

The toothed wheel 20 is flat, and its teeth slant in a different direction than the teeth of the wheel 20 above described with reference to Figures 1 to 3 inclusive.

Located adjacent the toothed wheel 20 is an actuating arm 32 and a chain arm 33, the actuating arm and chain arm being integral and together constituting a bell crank lever, connected with and used for actuating a valve 34. By means of a tensile spring 35, connected with the chain arm 33 and with the gas pipe, the bell crank lever has a tendency to maintain the normal position indicated for it in Figure 4, and it does maintain this position except when held by the toothed wheel 20.

A hand valve is shown at 36, and is mounted upon and controls a gas pipe 37 through which the gas is supplied.

The operation of the mechanism shown in Figures 4 and 5 is very much like that of the mechanism above described with reference to Figures 1 to 3 inclusive.

In order to light the gas, the operator first actuates the hand valve 36. This done the chain arm 33 is pulled down, so that the actuating arm 32 turns the toothed wheel 20 to a slight extent. The chain arm 33 be-

ing held down for a few moments, the gas is lighted by hand. The thermostatic element now becomes heated, and bends from the position indicated for it in Figure 4 to 5 the one indicated for it in Figure 5. This rocks the interference arm 28 from the position indicated for it in Figure 4 to the one indicated for it in Figure 5, and causes it to engage and hold the toothed wheel 20. 10 With the toothed wheel 20 thus held, the chain arm 33 can be released, and the burner will continue in action.

If, now, by means of a gust of wind or the like the gas flame is extinguished, the 15 change in form of the thermostatic element, due to its cooling, rocks the interference arm 28 out of engagement with the toothed wheel 20, so that this wheel releases the actuating arm 32. The spring 35 thereupon closes the 20 valve 34, and in so doing moves various movable parts into the normal positions indicated for them in Figure 4.

It will be noted that in each form of my device the actuating arm, for the purpose 25 of turning the toothed wheel, engages the radial edge (see 20^a, Figure 1) of one of the teeth, so as to insure a strong pull, by hand, against the radial edge; after the wheel 20 is thus turned the actuating arm, under tension 30 of its spring, rests gently against a slanting edge of one of the teeth, and is thus easy to dislodge from the wheel. It will also be noted that the interference arm, in engaging the toothed wheel 20 so as to prevent 35 the same from turning under spring tension, is pressed against sidewise by the radial edge of one of the teeth. This insures a positive grip between the interference arm and the toothed wheel, so that the interference arm is not likely to slip and by so doing 40 allow the gas to be cut off prematurely.

I do not limit myself to the precise mechanism shown, as variations may be made therein without departing from my invention, the scope of which is commensurate 45 with my claims.

I claim:

1. In a device of the character described the combination, with a gas burner, a gas 50 pipe leading to said burner, and a valve for controlling the flow of gas through said pipe to said burner, of a bell crank lever connected with said valve, a spring connected with said bell crank lever for shifting the same in a direction to close said valve, means controllable by hand for shifting said bell crank lever in a direction to open said valve, a supporting disk mounted upon said gas pipe, a wheel encircling said gas pipe and resting upon said supporting disk, said wheel being provided with teeth extending 55 partially into the path of travel of said bell crank lever, an interference arm journaled adjacent said wheel and movable into engagement with the teeth thereof to lock said

wheel and thus hold said valve open, and a thermostatic element mounted adjacent said burner and connected with said interference arm to shift said interference arm into and out of engagement with said toothed wheel, 70 thus locking and releasing said toothed wheel.

2. In a device of the character described the combination with a gas burner, a gas pipe leading to said burner, and a valve for controlling the flow of gas through said pipe to said burner, of a bell crank lever connected with said valve, a spring connected with said bell crank lever for shifting said bell crank lever to close said valve, means controllable by hand for shifting said bell crank lever to open said valve, a wheel encircling said gas pipe and provided with teeth each having a substantially radial edge and a slanting edge, said 80 teeth extending partially into the path of travel of said bell crank lever so as to enable said bell crank lever to engage the radial edge of one of said teeth and turn said wheel, an interference arm journaled adjacent said wheel and movable into engagement with the teeth thereof so that the radial edge of some one of said teeth lodges against said interference arm, thus locking said wheel and holding said valve open, and a thermostatic element mounted adjacent said burner and connected with said interference arm, to shift said interference arm into and out of engagement with 85 said teeth of said wheel, thus locking and releasing said wheel.

3. In a device of a character described the combination with a gas burner, a gas pipe leading to said burner and a valve for controlling the flow of said gas through said pipe to said burner, of a bell crank lever connected with said valve, a spring connected with said bell crank lever for shifting said bell crank lever to close said valve, means controllable by hand for shifting said bell crank lever to open said valve, a wheel mounted upon said gas pipe and provided with teeth each having a substantially radial edge and a slanting edge, said teeth extending partially into the path of travel of said bell crank lever so as to enable said bell crank lever to engage the radial edge of one of said teeth and turn said wheel, an interference arm journaled adjacent said wheel and movable into such 90 position that the radial edge of some one of said teeth lodges against said interference arm, thus locking said wheel and holding said valve open, and a thermostatic element comprising a pair of thermostatic bars located upon opposite sides of said burner, both of said thermostatic bars being connected with said interference arm, for the purpose of shifting said interference arm into and out of engagement with 95

100

105

110

said teeth of said wheel, thus locking and releasing said wheel.

4. In a device of the character described the combination with a gas burner, a gas pipe leading to said burner, and a valve for controlling the flow of gas to said burner, of a bell crank lever connected with said valve, a spring connected with said bell crank lever for shifting the same in a direction to close said valve, means controllable by hand for shifting said bell crank lever in a direction to open said valve, a supporting disk encircling said gas pipe, a wheel encircling said gas pipe and resting upon said supporting disk, said wheel being provided with teeth extending partially into the path of travel of said bell crank lever, each of said teeth being provided with a substantially radial edge and with a slanting edge, an interference arm journaled adjacent said wheel and movable into engagement with the teeth thereof for enabling some one of said teeth to lodge with its radial edge against said interference arm thus locking said wheel and holding said valve open, and a thermostatic element mounted adjacent said burner and connected with said interference arm, to

shift said interference arm into and out of engagement with said toothed wheel, thus locking and releasing said toothed wheel.

5. In a device of the character described the combination with a gas burner, a gas pipe leading to said burner, and a valve for controlling the flow of gas through the said pipe to said burner, of a bell crank lever connected with said valve, a spring connected with said bell crank lever for shifting the same to close said valve, means controllable by hand for shifting said bell crank lever to open said valve, a toothed wheel journaled upon said pipe for locking and releasing said bell crank lever, an interference arm for engaging and releasing said wheel, and a thermostatic element consisting of a pair of thermostatic bars extending upon opposite sides of said burner and both connected with said interference arm, for the purpose of shifting said interference arm into and out of engagement with said toothed wheel.

Signed at Akron, in the county of Summit and State of Ohio, this 12th day of January, 1924.

LOUIS HILL.
